DESIGN FOR A COMB OR THE LIKE

Joseph C. Foster, Leominster, Mass., assignor to Fosgood Corporation, Leominster, Mass., a corporation of Massachusetts

Application August 12, 1944, Serial No. 114,870

Term of patent 14 years

(Cl. D86—8)

To all whom it may concern:

Be it known that I, Joseph C. Foster, a citizen of the United States, residing at Leominster, in the county of Worcester, State of Massachusetts, have invented a new, original, and ornamental Design for a Comb or the like, of which the following is a specification, reference being had to the accompanying drawing, forming part thereof, in which:

Figure 1 is a front view of a comb or the like
embodying my new design;

Fig. 2 is a top plan view thereof; and,

Fig. 3 is an end view of the comb.

I claim:

The ornamental design for a comb or the like,
substantially as shown.

JOSEPH C. FOSTER.
